YORK.

METAL-HEATING APPARATUS.

1,302,843.

Specification of Letters Patent.

Patented May 6, 1919.

Application filed October 15, 1917. Serial No. 196,625.

To all whom it may concern:

Be it known that I, WILLIAM B. PEIRCE, a citizen of the United States, and resident of North Tonawanda, in the county of 5 Niagara and State of New York, have invented certain new and useful Improvements in Metal-Heating Apparatus, of which the following is a specification.

My present invention concerns metal-heating apparatus of the type shown in my 10 Patents 1,243,442, 1,243,443, and 1,243,444 issued on October 16th, 1917. The purpose is to progressively heat continuous lengths of material while feeding them automatically, into, through and out of a furnace.

Though useful for other purposes, it is particularly adapted for furnaces and operations where the metal is heated to a very high temperature, particularly where heated up to the softening point. Effective heating to such temperatures requires that the metal passing through the furnace be kept freely exposed on all sides to a very high heat for a considerable time. To do this 25 with the metal passing straight through the furnace would require either a very slow feed or a very long furnace, whereas it is desirable to use a relatively small, compact furnace and to give the metal a desired high rate of feed into and out of the furnace combined with a relatively slow rate of progress through the furnace.

For such purposes, it has been proposed to accomplish this by giving the metal a 35 straight feed into and out of the furnace, the intermediate portions being wound tightly around a revolving drum within the furnace. Such method involves extensive contact of the metal with the drum and prevents its free exposure and uniform heating on all sides. On the other hand, winding the metal in large, open, freely suspended coils in accordance with my present invention has not heretofore been attempted because of the difficulties resulting from the 40 initial stiffness of the metal and the effect of the heat in softening it.

My apparatus, while capable of useful employment for operations permitting tight 50 winding of the material on the drum, is of much greater importance and usefulness for operations requiring free suspension and exposure of the metal for effective, uniform,

high temperature heating. It involves giving to the material fed into the furnace a 55 predetermined initial shape and set in the curvature of a coil or helix of desired diameter and length suitable to the stiffness of the material and the size of the furnace. This material is wound into the furnace so 60 that it hangs loosely from a suitable support and, though the material is more or less flexible, the construction of the support is such as to permit the successive turn to assume and maintain a curvature and spacing roughly approximating the coil or helix shape originally given it.

By suitably predetermining the length of the interior support and the number of turns of the helix hanging thereon, the length of 70 time required for travel of each turn through the furnace may be as long as necessary. Hence, it is possible to maintain the required rate of output of heated material while using a relatively small, compact furnace.

Because of the effect of the heat upon the coiled material in softening it, it is necessary to carefully control the rates of movement of the metal at the supply end and the 80 exit end, so that it will be unwound from the exit end of the helix by the time it has become softened to the proper degree and before it becomes too soft to maintain proper separation of the turns of the helix.

The material is uniformly heated because the amount of it which actually touches the support is small and the point of contact is more or less shifting.

The material to be heated may be supplied in ready formed coils containing any desired length of the material, preferably the ordinary commercial coils obtainable from the rod mills. Such material already has an initial shape or set of approximately 90 the curvature of the coil in which it is marketed and such curved shape or set may be utilized in the formation of the desired helix within the furnace, the method of transfer into the furnace operating to progressively open out the coils to the desired 95 helical form.

The transfer of the material from the exterior coil to the interior helix may be effected, with or without change in the diameter of the turns, through an oblique open-

ing into the furnace, and this opening need not be of much greater diameter than the thickness of the material.

My invention may be used for progressively heating coiled material for any desired purpose, but it is particularly applicable to the heating of iron until it is soft enough for forging operations. In such case, it saves the necessity of straightening and cutting the coiled material into lengths, heating it in long furnaces and transferring it by hand to the automatic forging machine or other apparatus in which it is to be used.

15 The means for transferring the exterior coiled material into the furnace and for giving the successive turns the desired helical form is shown herein as consisting of an exterior rotor carrying an oblique opening 10 through which the coiled material in helical form passes into the furnace, the rotary path of said opening being in operative relation to an external support for the supply coil and an internal support for the helix which 20 is formed therefrom. The longitudinal support within the furnace is preferably non-rotating and preferably comprises a conical mandrel portion of approximately the diameter of the helix to be formed and upon 25 which the feed rotor lays the material to be heated in helical relation; and a more or less horizontal extension of much smaller diameter along which the successive turns of the helix progress in properly spaced 30 relation while exposed on all sides to the heat of the furnace. The fully heated material is withdrawn endwise from the remote end of the helix.

Means for accomplishing the above results 35 are shown in my Patent 1,243,443, but as will be evident by reference to said patent, the coil support is eccentrically located on the winder so that its axis is eccentric to the axis of the helical coil which it forms within 40 the furnace, and the rod coil is less than half the diameter of the winding mandrel. This requires that the initial curvature of 45 the coil must be very much straightened out in order to change the set of the material 50 to the large diameter of the winder, mandrel and helix formed thereby within the furnace. Such extensive straightening of the heavy rod material causes excessive 55 pressures and wear upon the guide surfaces and other parts of the mechanism and power 60 plant. Moreover, the eccentric or planetary relation of the coil support seriously unbalances the winding rotor thus creating a tendency to non-uniform speed of rotation

This and similar objectionable features were tolerated as necessary evils because the mechanical difficulties of maintaining the stationary mandrel out of contact with the furnace opening, yet within the path of the

rotary winder, seemed to render it impossible to apply the commercial bundle coils to the winder in any other way.

My present invention obviates these difficulties by employment of a transfer winder 70 comprising a transfer drum mounted on the axis of the rotary winder but rotatable independently of the winder so that both can be operated simultaneously without either interfering with the other. This transfer 75 drum is adapted to wind the coil off of an idle drum located in endwise relation thereto so that the transfer of the coiled rod material can be effected without much change of its set or curvature. This rewinding 80 drum has its surface approximately continuous with a coil support co-axial with the helix-forming rotor, so that the transferred coil can be slid endwise on to it from the transfer drum. This involves some increase 85 in the amount of apparatus employed, but commercially considered it is a great improvement since it makes it possible to have the coil support and coil winding substantially co-axial with the helical coil within 90 the furnace, and this permits transferring the continuous lengths of material from the commercial rod coil bundle, into the open helix on the support within the furnace, with only a minimum change in the initial 95 curvature or set, and hence with minimum wear of the parts and minimum power requirements.

Other features of my invention include 100 water cooling the margin of the circular opening in the furnace wall, in combination with the water cooling of the winding mandrel, thereby making it practical to use an air cooled cast iron surface instead of a fire brick surface on the rotor, as the closure 105 for the annular opening between said water cooled parts.

Other details of my invention including 110 the particular shape and proportion of the hanger within the furnace with reference to the furnace dimensions will be evident 115 from the following detailed description in connection with the accompanying drawings, in which—

Figure 1 is a plan view of the parts with 115 the furnace cut away to horizontal section on the level of the axis of the winder;

Fig. 2 is a side elevation of the same parts with the furnace cut away to vertical central section;

Fig. 3 is a vertical central section of all 120 of the operative parts as well as of the furnace;

Fig. 4 is a rear end elevation of the winding mechanism;

Figs. 5, 6 and 7 are details showing the construction of the annular face plate for closing the winding annulus between the mandrel and the circular furnace opening in which it is located; and

125

130

Fig. 8 is a detail elevation of the furnace door and the aperture through which the heated material is withdrawn.

In the various figures of the drawings, 5 similar parts are indicated by similar reference numerals.

The furnace in which the material is heated may be of any known or desired type. It preferably includes a reverberatory chamber 1 adapted to have its walls maintained at white heat by flaming gases and products of combustion introduced through the openings 2, 2 and 3, 3. The functions of fire brick regenerator shown at 4 need not 10 be described since these parts are only such as are commonly employed in regenerative reverberatory furnaces. The side walls 5, 6 and the end wall 7 are sloped inward to the bottom of the furnace so as to bring them 15 closer to the helical coil which is to be heated thereby but without danger of contact therewith.

The heating chamber within the furnace is of suitable dimensions to provide for a 20 helix of desired number, diameter and separation of turns and for an orderly withdrawal of the heated material therefrom.

The means for forming and supporting the desired helix of the material to be heated 25 within the furnace is preferably movably mounted with respect to the furnace upon a track 13. To this end, I provide a truck 14, mounted on wheels 15 carrying a massive standard 16. In the latter is rigidly secured 30 a forwardly extending hollow support 17 carrying the disk 18 upon which is mounted a conical mandrel 19 having an internal passage or chamber 20 continuously supplied with cooling water through pipes 21, 22 35 through the hollow support 17 and connecting with the interior of said mandrel through radial pipes 23, 24.

Extending forward from the uppermost portion of the annular mandrel 19 is a 40 hanger 25 in suitable relation for receiving the successive helical turns of the material and for holding them freely suspended and exposed to the heat on all sides. As will be evident from Figs. 1, 2 and 3, the hanger 45 comprises a U-shaped pipe in communication with the interior 20 of the mandrel 19, for free circulation of the cooling water. The hanger extends to about the middle of the heating space and the distance from its 50 free end to the exit opening is such that a loop of the helix when drawn off of the end will have space enough to hang in an open loop without danger of drawing a kink or forming a loop by welding contact. The 55 hanger slopes downwardly for about two-thirds of its distance to facilitate downward sliding of the successive turns of the helix under the influence of their own resiliency and the slight vibration imparted by operation of the machinery. This downwardly

extending portion of the hanger is narrowed so as to give shifting points of support for the loops thereby avoiding chilled spots in the heated material. The outer end of the hanger is inclined upwardly and is of diverging width so as to retard withdrawal of the material thereby making certain that draft upon the end of the material will throw off only one turn of the helix. 70

An important feature of the invention 75 which will be evident from Figs. 1 and 2 is that the exit opening through which the material is withdrawn is approximately in line with one side of the helix of heated material and on the level of the top of said helix. 80 Moreover, the side which it is on is selected with reference to the direction of winding of the helix so that the successive turns will be drawn straight off endwise with minimum recurring tendency. This means that if the 85 helix is wound in the direction of a left hand screw, the exit opening will be at the upper left hand side of the furnace.

The circular interior of the mandrel is formed so as to support the lining of fire-brick 19^a adapted to protect the supporting disk 18 and water pipes 23, 24 from the heat within the furnace and at the same time to furnish reverberatory heating surface for the interior of the furnace. 90

Upon the forward end of the support 17 is journaled the hub 26 of rotary disk 35, preferably through the medium of roller bearings 27.

The rotary disk 35 is formed or provided 100 with a circular peripheral bearing resting upon the anti-friction rollers 39, which may be mounted on truck 14. As shown, they are mounted on shafts 60, having at their opposite ends gears 61, 61, adapted to be 105 driven by pinions 62, 62, on shaft 63. Shaft 63 is driven through gear 64, 65, shaft 66, gear 67 and pinion 68 by electric motor 69.

The power is thrown on or off to control 110 the operation of these supporting rollers 39 by suitable clutches 70, 70, operated through links 71, 72, by lever 73.

As will be evident, the above described construction affords an ample interdependent support for the non-rotating mandrel structure above described as well as for the rotary disk. The rotor 35 has secured thereon by tension bolts 37, 37, opposed by thrust bolts 37', 37', an annular ring composed of cast iron segments 40 halved into each other as 120 at 41.

The above described structure mounted on the truck 14 forms a removable circular wall adapted to close the circular aperture 38 so as to minimize escape of flame and heated 125 gases during the operation of the device. Obviously, the major portion of the closure consists of the mandrel and fire-brick carried thereby, both of which are stationary when in operation although capable of long- 130

5 longitudinal movement with the truck. The segmental cast iron annulus 40 supplies a closure for the annular space around the mandrel. The circular margin of the opening in the furnace wall is provided with a water cooled ring 43 which, in conjunction with the water cooled mandrel keeps down the temperature of escaping gases to points sufficient to permit of the use of the air 10 cooled cast iron annulus as a means for closing the same.

On the stationary shaft 17 is mounted a coil support 79 which is preferably free to rotate independently of the winding head 15 35. Adjacent to the coil support 79, and of approximately the same diameter, is a transfer drum 81, rigid with a hollow shaft 80 and adapted to be driven by it through gears 83, 84, 85, shaft 87, gear 88, and gear 89. 20 The latter gear is mounted on shaft 63 and is adapted to be clutched to and unclutched from said shaft by operation of lever 90.

On the rear end of the vertical support is a stud 100 carrying an idle drum 101 upon 25 which may be placed the commercial bundle coils as they come from the rod mill. Between this drum and drum 81 is a guide 102 adapted to control the transfer of the rod material to said transfer drum 81.

30 In operation of the device, a bundle coil is placed on drum 101, passed through guide 102 and secured to transfer drum 81 as by twisting around one of the removable pins 103. The lever 90 is then operated to drive 35 the transfer drum thereby winding the rod material without much change of diameter and with only a slight lateral offset into a position where it encircles and is concentric with the axis of the winder and of the helix 40 to be formed thereby.

The pins 103 are now removed and coil slid on to the drum 79. The end of it is passed through oblique openings in the rotary winder and cast iron annulus 40. It 45 is then nipped between the presser-foot 46 and the mandrel 19. This presser foot is vertically movable as in my prior Patent 1,243,443 and may be cooled by water circulated through pipes 53 and 54. The lever 50 73 is then operated to start the supporting rollers 39 thereby rotating the winder.

A sufficient number of turns of the helix are thus deposited on the hanger and the free end brought out through the exit opening. 55

The number of turns and the speed of operation will be governed with respect to the heat of the furnace and the size of the material so that the material will be properly 60 heated by the time it reaches the end of the hanger.

Simultaneously with this operation, another rod coil bundle may be wound from drum 101 to transfer drum 81 in a manner 65 previously described. At suitable intervals,

the operation of the machine may be stopped for an instant while adjacent ends of successive coils are being held and welded in clamp 105 which may be an electric welder. The machine may then be restarted and the 70 operation will be continuous.

At the rear of the furnace is a door 110 through which the helical material may be manipulated either initially or during operation. At the side of the doorway is a 75 laterally and downwardly extending slot 112 in which the rod material may be inserted laterally. The portion of the slot unfilled by the rod is covered by the pivoted, gravity latch 113. 80

I claim:

1. A furnace for progressively heating material in coils, comprising a furnace having a circular opening, a mandrel in said opening supported independently of the 85 walls of the furnace, a winder adapted to deposit material shaped as an open helix upon said mandrel and means for supporting a supply coil co-axial with said winder and with the helix to be formed therefrom. 90

2. In an apparatus of the class described, a water cooled margin for the furnace opening, a water cooled mandrel and a sectional cast iron annulus for closing the annulus between said opening and said mandrel. 95

3. In an apparatus of the class described, a U-shaped water cooled hanger having laterally converging and diverging sides.

4. A furnace for progressively heating material in coils, including a furnace chamber having an annular opening, a support within said chamber for the coil to be heated an idle drum outside of said chamber, means for advancing material from said idle drum through said annular opening to 100 said coil support, a transfer drum adapted to be positively rotated to wind material thereon, said transfer drum being disposed co-axial with said idle drum whereby the coil may be shifted axially to the idle drum. 105

5. A furnace for progressively heating material in coils, including a furnace chamber having a coil support therein, a drum outside of said chamber for supporting a coil substantially co-axially with the coil in the 110 furnace chamber, means for transferring successive portions of the coil from said drum to said coil support, a second drum co-axial with the first mentioned drum, and means for positively rotating said second 115 mentioned drum to wind material thereon in the form of a coil, said coil being shifted axially from said second mentioned drum to said first mentioned drum.

6. A furnace for progressively heating 125 material in coils, including a furnace chamber having a circular opening and a truck having a closure for said opening, a coil support within said chamber, a drum outside of said closure, means for transferring 130

material from said drum to said coil support, a support for a supply of material, and means for winding said material in coiled form co-axial with said drum and in a position to be shifted axially on to said drum.

7. A furnace for, progressively heating material in coils, including a furnace chamber having a circular opening, a closure for said opening, a coil support within said 10 chamber, a drum outside of said closure, means for transferring material from said drum to said coil support, a support for a supply of material, and means for winding said material in coiled form co-axial with 15 said drum and in a position to be shifted axially on to said drum.

8. In a machine for progressively heating material in coils, a furnace chamber, a coil support therein, means for delivering material into said chamber on to said support substantially in the form of a helix with a substantially horizontal axis, said chamber having an exit opening in the wall thereof beyond said support and the helix thereon, 25 for the endwise withdrawal of the material of the coil, said opening being disposed approximately at the elevation of the upper side of the coil and at the side of the axis toward which the material at the upper side of 30 the coil would move if the coil were advanced as a screw.

9. A furnace for progressively heating material in coils, including a furnace chamber having a circular opening, a truck movable toward and from said opening and carrying a coil support adapted to extend into the furnace chamber through said opening, a source of power, means driven thereby for winding material in helical form outside of said furnace chamber, and independent means driven from said source of power

for advancing the material of the coil through said opening on to the coil support within the chamber.

10. A furnace for progressively heating material in coils, including a furnace chamber having an annular opening, a support within said chamber for the coil to be heated, a drum outside of said chamber, power-operated means for advancing material 50 from said drum through said annular opening to said coil support, a power operated transfer drum adapted to be positively rotated to wind material thereon, said transfer drum being disposed co-axial with said first 55 mentioned drum whereby the coil may be shifted axially to the latter drum, and means for starting and stopping said transfer drum without starting or stopping said means for advancing material to the coil 60 support.

11. A furnace for progressively heating material in coils, including a furnace chamber having an annular opening, a support within said chamber for the coil to be 65 heated, a drum outside of said chamber, power-operated means for advancing material from said drum through said annular opening to said coil support, a power operated transfer drum adapted to be positively 70 rotated to wind material thereon, said transfer drum being disposed co-axial with said first mentioned drum whereby the coil may be shifted axially to the latter drum, and means for starting and stopping said means 75 for transferring material to the coil support without starting or stopping said transfer drum.

Signed at North Tonawanda in the county of Niagara and State of New York this 13th 80 day of October, A. D. 1917.

WILLIAM BRADFORD PEIRCE.
